ATTORNEY.

UNITED STATES PATENT OFFICE.

JOSEPH B. KOFF, OF ROCKVILLE CENTER, NEW YORK.

HOPPLE.

Application filed July 12, 1922. Serial No. 574,513.

To all whom it may concern:

Be it known that I, JOSEPH B. KOFF, a citizen of the United States of America, residing at Rockville Center, New York, have 5 invented a new and useful Improved Hopple, of which the following is a specification.

My invention relates to so-called hopples for pacing horses and more particularly 10 consists in a new and improved safety buckle which is provided therewith to strengthen certain parts of said harness where heavy strain and breakage is sometimes likely to occur. Referring to the accompanying drawings,

Figure 1 is a perspective view of the general appearance of a hopple harness suitable for a pacer.

Figure 2 is the relatively enlarged perspective view of my improved tongueless buckle or clamp.

Figure 3 is an edge view of a portion of the harness showing conventionally the buckle as it would appear in use, the buckle 25 itself being shown in section.

1—1 and 2—2 illustrate respectively two pair of leg loops located at opposite sides of the harness. The loops of each pair are connected respectively by adjustable connecting straps, while said loops and connecting straps are properly supported by hanging straps 3—3 which go over the back of the horse and are provided with suitable buckles for adjustment.

35 My invention more particularly relates to the strengthening of the adjustable connecting straps, where, in the event the pacer should "break" into a trot or run, very heavy strain occurs and breakage of the 40 straps is not infrequent at the point or points where the belt is perforated for the tongue of an adjusting buckle. In the ordinary construction each adjustable connecting strap comprises an inside part 4 which 45 is secured, for example, to the rear leg loop. The free end is then passed through a so-called D-loop 5 and thence leads back to an ordinary adjusting buckle 6, by which the 50 overall length of the connecting strap may be lengthened or shortened at will. The outer part of the said strap is indicated as 4^a.

Inasmuch as with an ordinary tongue buckle it is necessary to puncture the strap to provide for the passage of the tongue, it 55 obviously weakens the strap at that point or points to a corresponding extent. Accord-

ingly, I provide a unique form of clamping buckle, which operates to take any excessive strain and thereby avoid this said danger. I have shown this clamping buckle in perspective in Figure 2, and it will be seen to comprise a horizontally elongated or rectangular loop 7 having end bars 7^a—7^a. 8 represents a rearwardly extending U-shaped member, having an end bar 8^a. The ends 60 of the member 8 are pivoted on the ends of a transverse pin 9, secured intermediate the length of the loop 7. The bar 8^a of the U-shaped member is secured to part 4 of the adjustable connecting strap in any 65 suitable manner, while the outside part 4^a of said strap is passed through the loop 7 from the rear and over the bar 9 as shown in Figure 3. In the event strain on the part 4 should become excessive it would tend to 70 pull the part 4 to the right relatively to part 4^a as shown in Figure 3. This movement, as will be seen by reference to the said Figure 3, will tend to swing the U-shaped member 8 on its pivot so as to crowd the 75 end bar 8^a of the U-shaped member toward the adjacent end bar 7^a of the buckle loop 7, thus clamping or pinching the two parts 80 4—4^a, of the connecting strap against each other so as to prevent slippage of the part 85 4^a in a direction that would tend to cause breakage at the tongue perforations.

It will be observed that the crossbar 8^a is offset from the bar 9 substantially to the same extent that the end bar 7^a is offset 90 therefrom, thus these two bars will mutually co-operate in tightly pinching together, or clamping, the two parts of the connecting strap as aforesaid.

What I claim is—

1. In a hopple harness, two leg loops with a two-part adjustable strap connection between the front and rear leg loops and including at least one buckle to permit said strap connection to be lengthened or shortened, and clamping means located intermediate the length of said two-part strap connection for pinching said two parts of said connection tightly together in the event of heavy strain thereon, to relieve the strain 100 on that part of said strap connected to said buckle.

2. In a hopple harness, two leg loops with a two-part adjustable strap connection between the front and rear leg loops and including at least one buckle to permit 110 said strap connection to be lengthened or

shortened, and clamping means located intermediate the length of said two-part strap connection for pinching said two parts of said connection tightly together in the event of heavy strain thereon, to relieve the strain on that part of said strap connected to said buckle, said clamping means comprising a loop having an intermediate cross bar, through which loop and over which bar one part of said strap is passed, and a swinging

U-shaped member pivoted to said loop, the other part of said strap being secured to said member, whereby excessive strain tending to slide one part of said strap on the other will cause said U-shaped member to swing toward the loop, to press the two parts of said strap connection into tight surface engagement for the purpose described. 15

JOSEPH B. KOPF.
